UNITED STATES PATENT OFFICE.

JASPER VAN WORMER, OF ALBANY, NEW YORK, ASSIGNOR TO J. VAN WORMER & CO., OF SAME PLACE.

PARLOR HEATING-STOVE.

SPECIFICATION forming part of Letters Patent No. 274,677, dated March 27, 1883.

Application filed June 27, 1882. (No model.)

To all whom it may concern:

Be it known that I, JASPER VAN WORMER, of the city of Albany, county of Albany, and State of New York, have invented a new and useful Improvement in Parlor Heating-Stoves, of which the following is a specification.

My invention relates to direct-draft parlor-stoves; and the object of my improvement is to better adapt them to burn bituminous coal and to furnish a means to heat a culinary vessel.

My invention consists, as will hereinafter be more fully described, mainly, in constructing the combustion-chamber of a direct-draft heating-stove with a pouch or offset feed-chamber, and with a horizontal top that is constructed to receive a culinary vessel, and an offset and outward extension of the combustion-chamber wall directly above the offset-feed, to receive 20 the exit-pipe connecting the stove with the chimney.

In the accompanying drawing, forming a part of this specification, there is shown a vertical section of a stove containing my invention, and in which illustration the several parts of the stove are designated by letter reference as follows:

D indicates the combustion-chamber wall, and C the combustion-chamber.

30 The letter O' designates a pouch-feed formed as an offset in the stove-wall D, and d its horizontal top provided with the opening B, the latter answering as a feed-opening and to receive a culinary vessel.

35 The letter E indicates the exit-flue formed on the offset O², constructed on the stove-wall directly above the pouch-feed.

The letter P indicates the fire-pot; G, the grate; a, a clinker-cleaning opening, and A 40 the ash-pit.

The letter C² indicates a dotted line that designates the contour of the stove-wall where the offset-pouch O' joins the latter.

Direction-arrows indicate the draft-currents 45 which support combustion and the course of the currents when the pouch-feed is opened.

The better results produced by a stove thus formed, as compared with the older construction of direct-draft stoves, are the following: 50 When cylinder-stoves, or "cannon-stoves," as they are sometimes called, are supplied with fuel through a vertical side door opening, smoke and gas will always escape into the room, from the fact that the draft force of the chimney

induces an entering current from the room 55 through the top of the vertical door-opening as the most direct course to the chimney, and as a sequence the smoke and gas eliminated from the fuel will pass into the room through the lower part of the door-opening. To obviate this escape of smoke and gas I construct the pouch-feed O' by means of an offset in the stove-wall, and provide this feed with a horizontal top, d, and supply-opening B. Directly 60 above this pouch-feed I construct the offset 65 O², and place thereon an exit-opening made to receive a vertical pipe. As thus constructed and arranged to co-operate, these combined parts produce a stove well adapted to burn bituminous fuel, and from which no escape of 70 smoke or gas can occur when being supplied with fresh fuel, from the fact that when the horizontal feed-top is uncovered there is an entering current across its top, as indicated by the arrows, and no egress-current of smoke 75 or gas through the feed-opening, one of the principal factors contributing to this better result being the offset-chamber to which the vertical exit attaches, in which no angles occur to produce interruptions and deflection of the 80 currents.

I am well aware that my invention does not broadly include the aggregation of the elements which I employ, but that it is limited to the manner in which I construct and relatively combine with the combustion-chamber of a direct-draft heating-stove a pouch-feed and an offset to receive an exit-pipe.

Having thus described my invention, what I claim, and desire to secure by Letters Patent, 90 is—

In a direct-draft parlor heating-stove having a fire-pot and grate, an inclosed combustion-chamber arranged above and connected with said fire-pot, a pouch-feed formed on the 95 combustion-chamber by the rearward extension of the latter, said pouch-feed having a horizontal top, and a feed-opening constructed to receive a culinary vessel or cover, and an offset-extension of the combustion-chamber, 100 directly above the pouch-feed, to receive the exit-pipe, constructed and arranged as herein shown and described.

Signed at Albany, New York, this 26th day of June, 1882.
